UNITED STATES PATENT OFFICE.

WILLIAM A. STUBBS, OF NEW YORK, N. Y., ASSIGNOR TO UNITED SHOE MACHINERY COMPANY, OF PATERSON, NEW JERSEY, A CORPORATION OF NEW JERSEY.

END-LASTING WIPER.

1,079,584.

Specification of Letters Patent.

Patented Nov. 25, 1913.

Application filed October 19, 1910. Serial No. 587,972.

To all whom it may concern:

Be it known that I, WILLIAM A. STUBBS, a citizen of the United States, residing at New York city, in the county of New York and State of New York, have invented certain Improvements in End-Lasting Wipers, of which the following description, in connection with the accompanying drawings, is a specification, like reference characters 10 on the drawings indicating like parts in the several figures.

This invention relates to machines for use in making shoes and particularly to end lasting apparatus. This apparatus as embodied in the bed type of lasting machines usually comprises end embracing wipers for the heel and the toe which present a substantially continuous wiping edge and are actuated to advance longitudinally of the shoe 20 and close inwardly from opposite sides to wipe the upper over the edge of the shoe bottom into position to be fastened.

The invention is here represented for exemplification as embodied in wipers of this 25 type which are adapted for lasting the heel portion of a shoe.

In lasting shoes over many styles of lasts in use at the present time, difficulty has been experienced in wiping the upper into proper 30 lasted position at the inner side of the shoe at the front of the heel and in the shank. This difficulty arises from the fact that the lasts referred to are cut under deeply at the inner side of the shank and the upper must be wiped far inwardly on 35 this side in order to work it into proper position to be secured to the innersole. For this purpose it is important for the wiper operating on the inner side of the shoe to 40 reach far forwardly. It is, however, not desirable that the wiper which acts on the outer side of the shoe shall reach so far forwardly for if it did so its closing movement would be obstructed by the rib on the 45 welt shoe and it would cover the tacking line on a McKay shoe.

In accordance with this invention lasting mechanism is adapted for positioning movement to present for action at one side 50 of the shoe a wiping edge which is substantially longer, or extends farther forwardly toward or along the shank, than the wiping edge presented for action at the other side of the shoe. In the illustrated embodiment 55 of the invention the wipers are provided

with extensions which are movable into and out of operative position alternatively. These wiper extensions constitute lasting devices which are movable into and out of position on a wiper to be carried by that 60 wiper over the shank of the shoe. Supplemental wipers having similar relations to the main wiper might be employed. As herein shown, however, the wiper extension is formed to present a continuation of the 65 acting edge of the main wiper when the extension is in operating position and is arranged to be turned backwardly into an inoperative relation when its use is not desired.

In the preferred embodiment of the invention a wiper extension is provided on the front end of each of the heel wipers, being pivotally connected thereto and having a construction coöperating with the construction of the wiper whereby it is rigidly held in operative position and is also retained in inoperative position when it has been turned into that relation to the main wiper.

The several features of the invention will 80 now be more fully explained in connection with the accompanying drawing and will then be pointed out in the claims.

Figure 1 is a plan view of a heel lasting mechanism embodying this invention; Fig. 85 2 is a perspective view of the under side of the wiper showing the extension in operative position and disclosing the formation of the wiper and its extension by which the latter is held rigidly against working 90 strains while in its operating position.

The heel lasting mechanism represented in the drawings is of a commercial type and requires no detailed description.

The wipers 2 are supported for sliding 95 movement forwardly and inwardly, which movement is imparted to them by link 4 connected by a cross-head 5 to an operating rod 6, which is moved by a hand lever, not shown. The wipers are so formed and 100 arranged as to present a continuous inner acting edge shaped to embrace the heel portion of a shoe and to lay the upper inwardly over the shoe bottom when they are advanced and closed. Each wiper, in accordance 105 with the illustrated embodiment of this invention, has connected to it by a screw 8 an extension piece 10 which when in its operative position presents an inner acting edge in continuation of the acting 110

2

edge of the main wiper plate. For securing this extension piece it is provided with a thin shank 12 and the wiper is formed with a pocket or recess extending forwardly from the screw 8 to receive the shank of the extension piece in a position in which the lower face of said shank and the lower face of the plate are flush with each other. The walls, and particularly the rear wall, of this pocket or recess form abutments which assist the screw 8 in maintaining the extension rigid against the strains which the extension piece is called upon to withstand during its operation. The wiper plate has also a pocket or recess extending rearwardly from the screw 8 and shaped to receive the extension piece in an inoperative position. By loosening the screw without necessarily detaching it from the extension piece the latter can be turned from its operative to its inoperative position or vice versa and then by tightening the screw it may be held firmly in the position to which it has been adjusted.

25 In a use of the invention which has been made with advantage the extension on that wiper which is to overwork the upper at the inner side of the shoe being lasted is shifted into its operative position and is employed for wiping the upper into the deeply cut shank of such lasts as are largely in use at the present time. It is the custom to last a case of shoes for the right foot and then to make the necessary adjustments of the machine for lasting shoes for the other foot. With the described use of this invention such adjustments will include the loosening of the screw 8, swinging of the extension piece which has been in use into the rear pocket in its wiper plate, and tightening the screw to maintain the extension piece in place in that condition. The extension piece for the other wiper which is now to work at the inner side of the shoes is then moved to its operative position. Obviously the extension pieces for both wipers could be continued in operative position while working on both right and left shoes if that were found convenient or both extension pieces could be rendered inoperative when their use is not desired. This invention furnishes wipers which in effect are of different lengths whereby a longer wiping edge is presented for action on one side of the shoe than on the other side. This is of importance in lasting shoes on many styles of unsymmetrical lasts, one example of such lasts having been herein referred to and illustrated in the drawing.

60 Having explained the nature of this invention, I claim as new and desire to secure by Letters Patent of the United States:

1. An end lasting mechanism comprising end embracing wipers adapted for positioning movement to present for action at one

side of the shoe a wiping edge which is substantially longer than the wiping edge presented for action at the other side of the shoe.

2. An end lasting mechanism having heel 70 embracing wipers of which that one which acts at the inner side of the shoe extends farther forwardly toward or along the shank than does the wiper which acts at the outer side of the shoe.

3. In an end lasting mechanism, end embracing wipers and end extensions removably attached to the wipers, substantially as described.

4. In an end lasting mechanism, end embracing wipers and extensions attached thereto and mounted for movement into and out of operative position upon the wipers.

5. In an end lasting mechanism, end embracing wipers and an end extension piece 85 mounted for positioning movement on a wiper, said wiper and extension piece being relatively formed to hold the extension rigid with the wiper when the extension occupies its operative position.

6. In an end lasting mechanism, end embracing wipers each having in one face a recess, and a wiper movably attached to said face and formed to fit against certain walls of said recess and be held rigid thereby 95 when in operative position and to be received between other walls of the recess flush with said face of the wiper when in inoperative position.

7. In an end lasting mechanism, end 100 embracing wipers, extensions therefor, means for attaching each extension to a wiper and a shoulder or wall on the wiper to resist displacement of the extension in the direction of its working strain.

8. In an end lasting mechanism, end embracing wipers, extensions therefor, and a pocket in said mechanism adjacent to the operative position of the extension to receive each extension when the latter is not 110 in use.

9. In an end lasting mechanism, end embracing wipers, operating mechanism to actuate the wipers forwardly and inwardly over the rear part of a shoe bottom, and 115 extensions for the wipers one of which can be moved into operative position to reach into the shank at the inner side of a shoe while the extension for the wiper that is located at the outer side of the shank is 120 inoperative.

10. In an end lasting mechanism, end embracing wipers, an extension for each wiper, a fastener securing the extension to the wiper, a pocket extending from the fastener 125 rearwardly to receive the extension in inoperative position and a second pocket extending forwardly to receive the extension in operative position, and a wall to back up the extension and position it, said fas- 130

tener being adapted to be loosened to permit the extension to be shifted from one pocket to the other without necessarily detaching it.

11. A heel lasting mechanism having, in combination, heel embracing wipers, operating mechanism therefor, and extensions adapted to be operatively positioned relatively to that wiper which is to overwork the upper on the inner side of the shank of the shoe and be actuated by said wiper operating mechanism when so positioned.

12. A heel lasting mechanism having, in combination, heel embracing wipers, operating mechanism therefor and a lasting device movable into and out of position on a wiper to be carried by that wiper over the shank of the shoe in front of the wiper.

13. A heel lasting mechanism having, in combination, heel embracing wipers, operating mechanism therefor, and a wiper end extension movable into and out of position to be actuated with the wiper for effecting a supplemental wiping action on the shoe.

14. A heel lasting mechanism having, in combination, heel embracing wipers having the extensions 10 movably supported thereon, to permit them to be shifted into and out of operative position separately, and the fastening 8 to secure the extensions in operative position.

15. An end lasting mechanism compris-

ing end embracing wipers and operating mechanism for advancing and closing the wipers for the purpose described, said lasting mechanism having provision for positioning movement to reach farther along one side of the shoe than along the other side.

16. An end lasting mechanism having, in combination, heel embracing wipers, operating mechanism therefor, means mounted for positioning movement to enable the wipers to reach farther forwardly along the shank edge of one side of the shoe than along the other side and arranged for actuation by said operating mechanism so to reach forwardly and overwork the upper differently on the two sides of the shank.

17. An end lasting mechanism having, in combination, end embracing wipers and actuating mechanism therefor, the end portion of each of the wipers being cut away on its lower side, and supplemental wipers mounted in the spaces so formed.

In testimony whereof I have signed my name to this specification in the presence of two subscribing witnesses.

WILLIAM A. STUBBS.
